(57) **CLAIM**

The ornamental design for a toothbrush container, as shown and described.

DESCRIPTION

FIG. 1 is a top view of a toothbrush container showing the new design assembled;

FIG. 2 is a right side view thereof, the left side view being a mirror image thereof;

FIG. 3 is a front view thereof, the rear view being a mirror image thereof;

FIG. 4 is a perspective exploded view thereof, showing a lid portion, a middle portion, and a bottom portion;

FIG. 5 is a right side exploded view thereof, showing the lid portion, the middle portion, and the bottom portion;

FIG. 6 is a left side exploded view thereof, showing the lid portion, the middle portion, and the bottom portion;

FIG. 7 is a front exploded view thereof, showing the lid portion, the middle portion, and the bottom portion;

FIG. 8 is a rear exploded view thereof, showing the lid portion, the middle portion, and the bottom portion;

FIG. 9 is a top view of the lid portion;

FIG. 10 is a bottom view of the lid portion;

FIG. 11 is a top view of the middle portion;

FIG. 12 is a bottom view of the middle portion;

FIG. 13 is a top view of the bottom portion; and,

FIG. 14 is a bottom view of the bottom portion.

The broken lines illustrate portions of the article that form no part of the claimed design.
